COOKING UTENSIL

Hubert J. Wiebe, 1926 Mentor 67213, and Max V. Gearheart, 1320 Summitlawn Court 67212, both of Wichita, Kans.

Filed Aug. 20, 1973, Ser. No. 390,070

Term of patent 14 years

Int. Cl. D7—02

U.S. Cl. D7—95

FIG. 1

FIG. 3

FIG. 2

FIG. 1 is a top perspective view of a cooking utensil showing one side and end of our new design;

FIG. 2 is a bottom perspective view showing the opposite side and opposite end; and

FIG. 3 is a partial sectional view taken through the upper right corner of the cooking utensil of FIG. 1.

We claim:

The ornamental design for a cooking utensil, as shown and described.
